UNITED STATES PATENT OFFICE.

ARISTIDE EUGENE GAREAU, OF MONTREAL, QUEBEC, CANADA.

MEDICAL-TREATMENT APPARATUS.

1,068,234.

Specification of Letters Patent.

Patented July 22, 1913.

Application filed September 3, 1912. Serial No. 718,265.

To all whom it may concern:

Be it known that I, ARISTIDE EUGENE GAREAU, a subject of the King of Great Britain, residing at Montreal, Province of Quebec, Canada, have invented certain new and useful Improvements in Medical-Treatment Apparatus; and I do hereby declare that the following is a full, clear, and exact description of the invention, such as will enable others skilled in the art to which it appertains to make and use the same.

The invention to be hereinafter described relates to medical treatment apparatus.

In order to more clearly disclose the construction, operation, and use of the invention, reference should be had to the accompanying drawings forming part of the present application.

Throughout the several figures of the drawings like reference characters designate the same parts.

In the drawings: Figure 1 is a front view of the invention; Fig. 2 is a side elevation; Fig. 3 is a central, vertical, longitudinal, cross section through the apparatus; Fig. 4 is a top plan view of the interior of the upper chemical chamber; Fig. 5 is a vertical cross section on line 5—5 of Fig. 4, looking in the direction of the arrows; Fig. 6 is a top plan view of the lower chemical chamber, with cover in place; Fig. 7 is a vertical cross section on line 7—7 of Fig. 6, looking in the direction of the arrows; Fig. 8 is a side elevation of an exhaust coupling or connection; Fig. 9 is a front view of a nose clip; Fig. 10 is a side elevation of the same; Fig. 11 is a central, vertical, longitudinal, cross section, enlarged, through one of the chemical cups; Fig. 12 is a top plan view of the slotted plate; and Fig. 13 is a central, vertical, longitudinal, cross section of the push rod.

The main objects of the invention are to provide a simple, efficient, durable, and economical apparatus whereby facial baths may be had without in any manner interfering with free breathing.

Referring to the drawings in detail, 1 indicates a suitable stand of any usual desired construction. In the top of this stand is seated a wash bowl 2, and at opposite sides of the bowl are securely supported two arm rests 3 of substantially U shaped construction in cross section. These rests are suitably braced by brackets, plates, or the like extending from the frame. The frame also

carries hot and cold water faucets 4 and 5 for delivering water to the wash bowl 2. The connections to this may be made in any of the various well known ways. If desired, a hot water vessel 6 may be secured to the top of the hot water faucet by means of a threaded connection in place of the regular handle, a turn plug being interposed in the connections. Then, if desired, the one faucet 4 may be used both for hot and cold water, by simply connecting the faucet with a cold water pipe and placing a turn plug 7 in the connections. Thus, when hot water is wanted from faucet 4 it is only necessary to close turn plug 7, fill receptacle 6, and open the turn plug in the connections between the receptacle 6 and faucet 4. For cold water the plugs are operated in the reverse order. The usual over flow pipe 8 leads from the upper part of the wash bowl, and a branch pipe 8' connects the bottom of the bowl with the over flow pipe 8 and is provided with any suitable turn plug or the like 9' for closing it while the bowl is in use. For examination and testing purposes, a waste pan 9 is removably seated in the lower part of the frame 1 and the over flow pipe 8 is adapted to be connected to this pan so that the contents of the bowl may be collected and examined. The bottom of the bowl is provided with an opening from which extends a short guide sleeve 10. In this sleeve is slidably mounted a tube 11. To one end of this tube is connected, by screw threads or otherwise, an upper chemical chamber comprising a cup 12, and a removable cover 13 with a hollow tubular mouthpiece 14 leading therethrough and communicating with the interior. The interior of this chamber is divided into two or more compartments by means of one or more partitions 15, and a nipple connection 16 is provided for each compartment to receive the end of a short flexible hose section 17 through which a chemical may be delivered from any suitable chemical cup 18.

As shown by the drawings, only two compartments and two cups are used. It is obvious that practically any desired number may be used. Within the chemical chamber and forming, practically, an extension of tube 11, is a bell shaped spreader 19, a series of perforations being provided in the wall of the spreader at the point where it is connected to the bottom of the chemical chamber, for a purpose to be later disclosed.

To the lower end of the tube 11 is removably connected the top 20 of the lower chemical chamber. The lower or cup shaped body 21 is removably connected to its cover 20 by screw threads or the like and is provided with a tapered valve seat 22 to receive a ball valve 23 which controls the passage through a tubular stem 24 provided with external threads for connection of a hood 25. The wall of the valve seat 22 is provided with a series of lateral passages 26 for a purpose to be later disclosed. The cup shaped body 21 is provided with a nipple connection 27 to receive one end of a flexible hose connection 28 by which a chemical 10 may be supplied to the lower chemical chamber from any one of the chemical cups 18. In the top 20 is removably seated a small tubular perforated exhaust tube 29 provided with a ball valve 30 for normally closing the passage from the chemical chamber through the tube. From the above, it will be seen that, when the ball valve 23 is raised, there is a clear passage through the tube 11 from beneath hood 25 to and through the mouthpiece 14. Beneath hood 25 is a basin 31 mounted on an upright tube 32 extending upwardly from the pan 9 and provided with perforations or openings in its upper and lower ends. On the upper end of the tube is removably seated a cup 33. In this cup and on the inner wall of the basin are mounted suitable sponge baskets to hold sponges or other absorbents charged with volatile chemical.

In use, a quantity of lime or other air purifying substance is placed in the bottom of the basin and water is turned on it to start chemical action. Water is delivered 40 to the basin by means of a branch pipe 34 swiveled to either the hot water pipe or the cold water pipe—preferably to the cold water pipe. The free end of the branch pipe is made as a U to allow it to fit down over the edge of the basin. The swiveled connection permits it to be swung out of the way so that the basin 31 may be lifted up without interference. In order to drain off the liquid from the basin 31, from time to 45 time, a by-pass 35 is provided, having its opposite ends connected to the tube 32 and the bottom of the basin 31, respectively. From the upper end of this by-pass projects a small perforated tube 36 which acts as a 50 strainer to prevent passage of solid matter from the basin into the by-pass. A suitable turn plug 37 may be used to control the by-pass.

In order to raise the hood 25, and bring 60 the mouthpiece 14 into position to be taken into the patient's mouth, a combination of lever, yoke, and push rod is provided. This comprises a yoke 38 extending from an arm 39 on a rock shaft 40 journaled in the frame 65 and operated by a push rod 41 connected to

another arm 42 of the same rock shaft. The ends of the yoke are provided with arcuate slots 43 in which are slidably mounted pins or screws 44 projecting from the collar 45 of the hood. By depressing the push rod, the hood 25 and mouthpiece 14 will be raised, as will be obvious. In order to hold the push rod depressed, a special means is provided. This comprises a sleeve 41' rotatably mounted on the push rod 41 and provided with a holding pin 46 adapted to pass through a notch 47 formed in the wall of the opening 48 which is provided for the passage of the push rod through a plate secured in one of the arm rests.

In operation, the push rod is forced down until the pin passes through the notch 47 and it is then turned until the pin is out of alignment with the notch, thus holding the rod down. In order to limit the relative 35 rotary movement between the rod 41 and sleeve 41', a short arcuate slot is provided in the lower part of the sleeve to receive a limit and connecting screw 49 passed through the slot and threaded into the rod, as clearly 40 shown in Fig. 13. The pan 9 is provided with the usual outlet pipe 50 having a controlling turn plug 51. In cases where it is not desired to examine the fluid coming from the wash bowl 2, the pan 9 is omitted and 45 plumber's trap 52 is substituted. The tube 32 is seated in the top of the trap and the tube 8 is provided with a T coupling 53 connecting it to the outlet pipe 54 leading from the lower end of the trap. While the 50 patient's face is immersed in the fluid of the bath it is necessary, of course, to close the nostrils to prevent all tendency to inhale the fluid. For this purpose, a pair of nose clips such as those shown in Figs. 9 and 10 are 55 used. These are simply fastened on the patient's nose by gripping the two short arms and forcing them together to spread the long arms so that they may receive the patient's nose, and then releasing the short 60 arms so that the longer arms may be forced together to compress the nostrils of the patient. The arms are actuated by a coil 65 spring 55, of course.

The chemical cup is of the usual standard 70 construction, as shown in Fig. 11, and, therefore, needs no further description.

The operation of the invention is as follows: The push rod is operated to raise the mouthpiece 14 to its highest point and then 75 turned to hold it raised; the turn plug 9' is then closed; the bowl 2 is filled with the desired medicinal bath; the basin 31 is supplied with water to cause chemical action of the purifying substances; one or both of the 80 chemical chambers is charged; the nose clips are placed on the patient's nose; the patient takes the mouthpiece 14 in his mouth; and the push rod is operated to lower the mouthpiece, drawing the patient's face beneath the 85

surface of the bath. While thus immersed, the patient breathes through the mouthpiece 14 and connected tube, chambers, and hood, the deflector 19 acting to prevent too direct an inhalation of the chemically charged air. As the patient inhales, the valve 23 will be slightly unseated and the valve 30 snugly seated. This will compel the air to come up through the tube 11 from beneath the hood 25. The air beneath the hood 25 is first purified by the substances in the basin 31 and then chemically charged by the substances on the sponges, and then further chemically charged by the chemicals in one or the other 15 or both of the two chemical chambers. These chemicals, of course, may be suited to a wide variety of treatments. Now, as the patient exhales, his breath will pass into the funnel end of the deflector 19, down through tube 20 11, seat valve 23, unseat valve 30, and exhaust through the perforations of the exhaust tube 29. Thus, the operation of the valves 23 and 30 is automatic and operated entirely by the breathing of the patient. 25 Also, it will be seen that the action of the part 19 is twofold—*i. e.* it acts as a deflector or spreader of the chemical laden air, and as a collector of the exhaled breath of the patient. 30 One of the objects of having both an upper and a lower chemical chamber is to provide a means for more or less regulating the strength of the application. With some chemicals, the use of the upper chamber may 35 make the application too direct and too strong, whereas, when used in the lower chamber the application becomes less direct and milder. Also, the choice of the upper or lower chamber may depend considerably 40 upon the condition of the patient, or the ailment under treatment. During treatment, the patient simply rests his arms in the supports 3, of course.

It is obvious that the entire outfit or set 45 of chemical appliances may be omitted and a simple mouthpiece provided directly on the upper end of the tube 11, and only the usual untreated air breathed through the tube while the face is immersed either in a 50 plain hot water bath, or a mineral water bath, or a chemical bath, as desired. In such case, the lifting yoke may be connected to the lower end of the tube 11, instead of to the hood.

55 It is thought that the operation and use of the invention will be clear from the preceding detailed description.

Changes may be made in the construction, arrangement, and disposition of the several 60 parts of the invention without in any way departing from the field and scope of the same, and it is meant to include all such within this application wherein only a preferred form has been disclosed.

65 Having thus fully described my invention,

what I claim as new and desire to secure by Letters Patent is:

1. An apparatus of the character described comprising, a frame, a bowl mounted in the frame, a breathing tube slidably mounted in said bowl, means for raising said tube, and means for securing said tube in raised position. 70

2. An apparatus of the character described comprising, a frame, a bowl mounted therein, a tube slidably mounted in said bowl, a chemical chamber carried by said tube, and a mouthpiece communicating with said chemical chamber. 75

3. An apparatus of the character described comprising, a frame, a bowl mounted therein, a tube slidably mounted in said bowl, a chamber carried by the lower part of said tube, means for compelling exhaust of respirations from said tube through said chamber, a hood carried by said tube below said chamber, and a basin supported beneath said hood. 80

4. An apparatus of the character described comprising, a frame, a bowl mounted therein, a breathing tube slidably mounted in said bowl, a chamber carried by the lower part of said tube, means for compelling exhaust of respirations from said tube through said chamber, a hood carried by said tube below said chamber, a basin supported beneath said hood, and means for raising the aforesaid tube. 90

5. An apparatus of the character described comprising, a frame, a bowl mounted therein, chemical cups mounted on said frame, a tube slidably mounted in said bowl, a chemical chamber carried by said tube, means for delivering chemicals from said cups to said chamber, and a mouthpiece communicating with said chamber. 100

6. An apparatus of the character described comprising, a frame, a bowl mounted therein, a tube slidably mounted in said bowl, a chemical chamber carried by said tube, a deflector within said chamber, and a mouthpiece communicating with said chemical chamber. 105

7. An apparatus of the character described comprising, a frame, a bowl mounted therein, arm rests carried by said frame adjacent said bowl, and a tube slidably mounted in said bowl. 115

8. An apparatus of the character described comprising, a frame, a bowl mounted therein, a tube slidably mounted in said bowl, a rock shaft journaled in said frame, a yoke carried by said rock shaft and adapted to lift said tube, an arm carried by said rock shaft, and a push rod carried by said arm. 120

9. An apparatus of the character described comprising, a frame, arm rests carried by said frame, a bowl mounted in said frame, a tube slidably mounted in said bowl, 130

a rock shaft journaled in said frame, a yoke carried by said rock shaft and adapted to lift said tube, an arm carried by said rock shaft, a push rod connected to said arm, a sleeve rotatable about said push rod and slidably mounted in one of the aforesaid arm rests, means connecting said push rod and said sleeve and adapted to permit limited rotary movement of said sleeve about said 10 push rod, and means for holding said push rod in lowered position.

10. In combination with an apparatus of the character described, a tube, an upper chemical chamber carried thereby, a mouth-piece carried by said upper chamber, a lower chemical chamber carried by said tube, and an exhaust carried by said lower chemical chamber.

11. An apparatus of the character de-

scribed comprising, a frame, a bowl mounted therein, arm rests carried by said frame, a tube slidably mounted in said bowl, an upper chemical chamber carried by said tube, means for supplying a chemical to said upper chamber, a mouthpiece carried by said upper chamber, a lower chemical chamber carried by said tube, means for supplying a chemical thereto, an exhaust carried by said lower chamber, a hood suspended from said lower chamber, a basin beneath said 30 hood, a yoke connected to said hood, and means for operating said yoke.

In witness whereof I have hereunto set my hand in the presence of two witnesses.

ARISTIDE EUGENE GAREAU.
